UNITED STATES PATENT OFFICE.

GEORGE R. BOWEN, OF SAN ANTONIO, TEXAS.

DESIGN FOR A HANDKERCHIEF, &c.

SPECIFICATION forming part of Design No. 25,754, dated July 7, 1896.

Application filed October 18, 1895. Serial No. 566,149. Term of patent 31 years.

To all whom it may concern:

Be it known that I, GEORGE R. BOWEN, a citizen of the United States, residing at San Antonio, in the county of Bexar and State of Texas, have invented a new and original Design for Handkerchiefs, Napkins, Fans, &c., of which the following is a specification.

This invention relates to a new and original design for handkerchiefs, fans, napkins, cards, and similar articles; and it has for its object to provide a design of this character that shall be both useful and ornamental. The leading feature of the design resides in a large rectangular space having centrally arranged therein a circularly-shaped figure, which circularly-shaped figure is partly encircled at opposite sides by wreaths extended upwardly from the representation of bunches of flowers arranged on a circle below said central circular figure; the representation of an Indian head confined within the outlines of the central circular figure; the representation of a lion at one side of the central circular figure, and on the head of which lion is represented a regal crown, and at the opposite side of the central circular figure facing the representation of the lion, the representation of a unicorn; scroll-shaped figures arranged directly under the representations of the lion and the unicorn; representations of sinuously-curved tails of the lion and the unicorn projected from opposite top sides of the central circular figure, and the representation of a crown in the space between the said tails; the representations of a money-safe and a superadjacent child disposed in the space above the central circular figure, and in the corresponding space below the central circular figure a representation of an altar represented as supporting the figure of a bull having boots on the legs and a beaver hat supported on the head between the horns; representations of a pair of oppositely-disposed unfurled flags arranged within each corner of the large rectangular space and having their staffs crossed at a point intermediate of their ends, and groups of three small circularly-shaped figures scattered throughout the plain portions of the large rectangular space.

The drawing represents a face view of the design contemplated by this invention.

Referring particularly to the drawing, the numeral 1 designates a large rectangular figure or space bounded by a wide marginal border 2, and located centrally within the large rectangular space 1 is a circular figure 3, partly encircled at opposite sides by wreaths 4, extended upwardly from the representation of bunches of flowers 5, arranged on a circle below the central circular figure. The central circular figure 3 has confined within the outlines thereof the representation of an Indian head 6, and at one side of the figure 3 is represented the figure of a lion 7, on whose head is represented a regal crown 8. At the side 65 of the figure 3, opposite the figure 7, is represented a unicorn 9, facing toward the representation of the lion, and below each of the representations 7 and 9 are scroll-shaped figures 10. The lion and unicorn are represented as having sinuously-curved tails 11, which are projected from opposite top sides of the central circular figure 3, and in the space between the tails 11 is represented a second regal crown 12. Above the central part of the design just described appears, respectively, the representation of a money-safe 13 and a superadjacent child 14, while in a corresponding position below the central part of the design appears the representation of an altar 15 and the representation of a bull 16 on top of the altar. The figure of the bull is represented as having boots 17 on each leg and a beaver hat 18 supported on the head between the horns. In each corner of the large rectangular space 1 appears the representation of a pair of oppositely-disposed unfurled flags 19, having their staffs 20 crossed at a point intermediate of their ends, and the design is completed by groups of three small circularly-shaped figures 21, scattered throughout the plain portions of the large rectangular space.

What I claim is—

The design for handkerchiefs, fans, and similar articles, as herein shown and described.

In testimony that I claim the foregoing as my own I have hereto affixed my signature in the presence of two witnesses.

GEO. R. BOWEN.
